UNITED STATES PATENT OFFICE.

JOSEPH L. WRIGHT, OF CLEVELAND, OHIO, ASSIGNOR TO WESTERN ELECTRIC COMPANY, INCORPORATED, A CORPORATION OF NEW YORK.

TELEPHONE-EXCHANGE SYSTEM.

1,274,654.

Specification of Letters Patent.

Patented Aug. 6, 1918.

Application filed October 6, 1914. Serial No. 365,261.

To all whom it may concern:

Be it known that I, JOSEPH L. WRIGHT, a citizen of the United States, residing at Cleveland, in the county of Cuyahoga and

5 State of Ohio, have invented certain new and useful Improvements in Telephone - Exchange Systems, of which the following is a specification.

My invention relates to telephone exchange systems employing automatic switching mechanism for interconnecting subscribers' lines. My invention is applicable to such systems whether of the full automatic or semi-automatic types.

10 15 The manner in which the switches are controlled allows two-wire or metallic circuits to be used. In systems employing such circuits for controlling the automatic switches it has been customary to employ a

20 25 combination of slow and quick acting relays. The quick acting relays are responsive to rapid makes and breaks in the metallic circuits caused by the sending devices and in turn transmit these impulses to the control magnets of the automatic switches to cause

30 them to assume a predetermined position. The slow acting relays act in response to current changes of long duration produced at the sending devices and shift the various circuits at the automatic switches and serve to control their release.

With my invention no slow acting relays or retarded devices are used. The impulses from the sending devices which are produced by simply making and breaking the metallic circuit operate designating devices associated with the automatic switches at the central office.

Each automatic switch is provided with 40 its individual stepping or actuating circuit and the switch so operated by this circuit simply steps at its own speed and selects a particular contact. Each switch is provided with the ordinary test and trunk contacts.

45 In addition to these contacts designating contacts are provided for determining the particular point or contact at which the switch should come to rest.

These designating contacts are rendered 50 active or selectable by the operation of the designating devices before referred to.

The designating devices respond to the impulses and render the designating contacts selectable according to the number of 55 impulses transmitted by the sending devices.

After such contacts are rendered selectable the automatic switches travel at their own speed and after selecting the active contact cause circuit changes to be effected.

In case of a selector switch, the circuit 60 change serves to connect the testing circuit and allows the switch to automatically pick out an idle trunk in the designated group.

In case of a connector switch, both the group and individual contacts in the group 65 are rendered active or selectable by the designating device. This arrangement allows a predetermined individual contact in the group to be selected.

In the present instance I have shown my 70 invention applied to a system of the full automatic type, but, of course, it can be equally well applied to systems of the semi-automatic type.

For illustration I have shown in detail 75 the designating means as consisting of a group of step-by-step relays. Relays of this character and for selective purposes are shown in Patent No. 965,976 to J. L. Wright, of August 2, 1910.

80 My invention is illustrated in the accompanying drawings, wherein:

Figure 1 shows a subscriber's line equipment.

Fig. 2 shows a first selector switch and 85 its associated designating device.

Fig. 3 shows a connector switch and its associated designating device.

Fig. 4 shows the wiring of the designating contacts associated with a connector 90 switch.

Fig. 5 shows a modified form of designating means consisting of a step-by-step switch.

Referring to Fig. 1, the subscriber's station AA is equipped with apparatus usual in common battery systems and in addition is provided with a sending device. In the present instance I have designated this device by means of a push button 40. The 95 operation of the sending device serves to open and close the line conductors and so cause impulses to be transmitted to control the automatic switches.

The first selector switch J (Fig. 2) is of 105 the two-motion type. It first rotates to select the proper group of contacts and then steps vertically to select a particular contact in the group. The row wiper 33 sweeps over the row designating contacts while the 110

switch is rotating and when an active contact is engaged, the rotary action of the switch is arrested and it then steps in a vertical direction.

5 The designating device consists of the step-by-step relays marked K, 1—K, etc., and L, 1—L, etc. In the present instance I have shown but five sets of these relays, and, consequently, have shown but five row 10 designating contacts in association therewith. In practice, however, there would be ten row designating contacts such as shown in Fig. 4. In providing ten contacts there would, of course, be ten sets of step-by-step 15 relays.

The designating relays are controlled by relay A, which responds to impulses transmitted at the subscriber's station.

Fig. 3 shows a connector switch X and 20 its associated set of designating relays R, 1—R, etc., and S, 1—S, etc. In the present instance I have shown but three sets of designated relays and three sets of row and individual designating contacts associated 25 with the switch X. In practice, however, there would be ten sets of contacts and ten sets of designating relays.

The designating contacts in the connector switch X are arranged and connected in accordance with Fig. 4. No. 1 row contact is 30 connected in multiple with No. 1 individual contact of each row or group. The same arrangement is made in connection with the remaining row and individual contacts. 35 These row and individual contacts are rendered active or selectable by the same set of designating relays.

The switch X like switch J also first rotates and then steps in a vertical direction.

40 Fig. 5 shows how designating contacts are rendered selectable by means of a step-by-step switch 500. The magnet 501 of this switch responds to the impulses caused by the sending device and engages a particular 45 contact in the bank of a selector or connector switch, as the case may be. As soon as the designating contact is selected by the selector switch, relay 5—M is operated and closes the circuit of the release magnet 6—M, there- 50 by causing the switch 500 to restore.

The details of the various circuits can best be understood by describing the operation of the apparatus in tracing a call from a calling to a called subscriber. For illustration we will assume that subscriber at station AA desires to converse with a subscriber whose number is 3—2—1.

The subscriber at station AA removes his receiver and then operates the sending device 60 to transmit three impulses.

The removal of the receiver closes the line circuit and causes the operation of relay A. The operation of relay A completes the circuit of the locking relay C by the following 65 path: ground, contacts of relay A, 25, cam

springs 40, 26, winding of relay C to battery B. Relay C after operating remains locked to ground through the back contacts of relay M. The operation of relay C connects battery to the locking contacts of the set of relays L, 1—L, etc., and K, 1—K and also connects battery to a contact of relay A. 70

The subscriber at AA in operating his sending device causes relay A to respond and transmit impulses to the set of designating relays. During the first impulse when relay A restores, the circuit of relay L is completed by the following path: battery B, contacts of relay C, 9, contacts of relay A, 10, contacts of relay K, 11, winding of relay 80 L to ground. The operation of relay L places relay K in condition to be operated at the next energization of relay A by the following path: battery B, contacts of relay C, 9, contacts of relay A, 12, contacts of relay L, 13, contacts of relay 1—L, 14, winding of relay K to ground. The operation of relay K connects ground to No. 1 row contact of the switch J by the following path: ground, contacts of relay 4—K, 3—K, 2—K, 90 1—K and K. The operation of relay K also completes the circuit of the rotary magnet E of the switch J by the following path: ground, contacts of relay K, 29, winding of magnet E, 30, contacts of relay F to battery B. 95

The next impulse transmitted at the substation causes relays 1—L and 1—K to be operated and the operation of the latter relay causes ground to be connected to No. 2 100 row contact of the switch J and to be removed from No. 1 contact. The next impulse at the substation causes relays 2—L and 2—K to be operated, and the operation of the latter relay causes ground to be disconnected from No. 2 contact but connected to No. 3 contact.

It will be noticed that the operation of relay K completes the circuit of the rotary magnet E. The operation of this magnet 110 causes the switch J to step in a rotary direction. At each operation of the magnet E the relay F has its circuit completed by contacts associated with the magnet and in operating opens the circuit of the magnet. 115 This coöperation between the relay and the magnet causes a vibrating effect and the vibration of the magnet E causes the switch J to step accordingly.

The impulses, however, which are transmitted at the substation are at a faster rate or in advance of the stepping of the switch J controlled by the magnet E, and, consequently, the ground connections to the various row contacts are always shifted in advance of the row wiper 33. After the first set of impulses have been transmitted, however, and which in the present instance are three in number, there is an interval caused by the subscriber setting the sending device 125 130

for the next set of impulses. During this interval the wiper 33 engages No. 3 contact which was grounded by the operation of relay 2-K. As soon as connection is effected 5 with this contact the circuit of relay M is completed and it in operating remains locked to ground through contacts of the release magnet H of the switch J. The operation of relay M removes ground from the locking 10 contact of relay C and this relay in restoring removes battery from the locking contacts of the set of designating relays. These relays which were energized by the transmission of three impulses from the substation restore 15 and the restoration of relay K opens the circuit of magnet E, causing the switch J to come to rest with its wipers 34, 35 and 36 in line with the proper row or group of contacts leading to connector switches. 20 The operation of relay M completes the circuit of the test relay D of the switch J by the following path: ground, contacts of relay M, cam springs 45, winding of relay D to battery B. The operation of relay D completes 25 the circuit of the vertical stepping magnet G of the switch J. This magnet in operating closes its associated contact springs and operates relay F, and this relay in operating opens the circuit of the magnet itself. This action between the relay and the magnet causes a vibrating effect and the 30 operation of the magnet causes the switch J to step vertically until relay D restores. This relay restores when the test wiper 34 engages an idle contact leading to a connector switch. As soon as such a contact is 35 found relay D restores, thereby opening the circuit of the magnet G and causing the switch J to come to rest and engage contacts leading to an idle connector switch. The 40 restoration of relay D completes the circuit of the cut-off relay N by the following path: ground, contact of relays D and M, 23, winding of relay N to battery B. The operation 45 of relay N removes battery and ground respectively from the windings of relay A and the coil I.

From the foregoing it will be noticed that as soon as connection is effected with an idle 50 trunk, the battery supply relay and coil are disconnected from the tip and sleeve conductors, thereby allowing a clear circuit extending to the connector switch. The operation of relay M and the deenergization of 55 relay D also allows ground to be connected to the test contacts associated with the connector switches so as to prevent the calling line being selected by other calls.

When the first selector switch J engages 60 contacts leading to an idle connector switch, relay Y has its circuit completed as follows: battery B, resistance coil 100, winding of relay Y, test contacts 34, contacts of relay D, 7, winding of magnet H to ground. Relay Y is of low resistance, but is adjusted to

operate in series with the winding of the coil 100 and the winding of the magnet H. The magnet H, however, is so adjusted that it will not operate in series with the winding of the relay Y and the coil 100, but it will, 70 however, operate in series with the winding of relay Y alone. In addition to relay Y becoming energized as soon as the connector switch is selected, relay 1-A will also be operated as it has its winding connected 75 directly to the tip conductor and supplies battery to the calling line while the coil 1-I supplies ground to the other conductor extending to the calling line. The operation of relay 1-A completes the circuit of the 80 locking relay 1-C by the following path: ground, contacts of relay 1-A, 77, winding of relay 1-C, 76, contacts of relay 4-M to battery B. The operation of relay 1-C connects battery to the contact of relay 1-A 85 which controls the operation of the set of relays R, 1-R, etc., and S, 1-S, etc.

The subscriber at station AA operating his sending device the second time causes two impulses to be transmitted, thereby operating relay 1-A accordingly. Relay 1-A restoring during the transmission of the first impulse completes the circuit of relay S by the following path: battery, contacts of relay 1-C, 64, contacts of relay 1-A, 201, contacts of relay R, 69, winding of relay S to ground. The operation of relay 1-A following the transmission of the first impulse completes the circuit of relay R by the following path: battery, contacts of relay 1-C, 64, contacts of relay 1-A, 65, contacts of relay S, 66, contacts of relay 1-S, 67, winding of relay R to ground. The next impulse 95 operates relays 1-S and 1-R. The operation of this latter relay connects ground to 100 No. 2 row contact by the following path: contacts of relays 2-R and 1-R, 84, No. 2 row contact. The operation of relay R completes the circuit of the rotary magnet U of the switch X by the following path: 110 ground, contacts of relay 4-M, contacts of relay R, contacts of relay 2-M, 97, winding of magnet U, 98, contacts of relay V to battery B.

The operation of magnet U causes its associated contact springs to be closed, thereby operating relay V, which in turn opens the circuit of the magnet U. This action causes a vibrating effect between the magnet and relay and the operation of the former causes 115 the switch X to rotate. As soon as the row wiper 110 engages No. 2 contact, which is grounded, then relay 1-M is operated. The operation of this relay disconnects battery from the locking contacts of relays S, 1-S, 120 R and 1-R, thereby causing them to restore. The restoration of relay R opens the circuit for controlling the stepping magnets of the switch X. The operation of relay 1-M also completes the circuit of relay 2-M by the 125 130

following path: ground, contacts of relay 1—M, 70, winding of relay 2—M to battery B. The operation of this relay disconnects the rotary magnet U and in its place connects the vertical magnet W.

From the foregoing it will be noted that after the second group of impulses have been transmitted and the designated row has been selected by the row wiper 110 then the designating relays are released and the circuit of the vertical magnet W substituted for that of the rotary magnet U.

The subscriber at station AA transmitting one impulse operates relay 1—A accordingly, which in turn causes the operation of relays S and R. The operation of relay R connects ground to No. 1 contact in the designated row, and also completes the circuit of the vertical magnet W of the switch X. The operation of the magnet W causes the switch X to step vertically and when the wiper 115 engages No. 1 contact, which is grounded, then relay 3—M has its circuit completed and in operating completes the circuit of relay 4—M. The operation of this relay (4—M) opens the circuit of the vertical magnet W of the switch X, causing the wipers to rest on contacts leading to the called-for line.

In case the called-for line is busy then the test relay O will be operated by current flowing over the following path: ground, test contacts of the called line, test wiper 105, contacts of relay 3—M, winding of relay O to battery B.

The operation of relay O completes the circuit of the release magnet P, thereby causing the restoration of the switch X. The operation of this relay also connects a suitable busy tone test to the trunk conductor notifying the calling subscriber that the called-for line is busy. The relay O remains locked to ground through the contacts of relay Y. Relay Y is deenergized when the calling subscriber replaces his receiver and it in restoring releases relay O.

In case the called-for line is not busy then relay O will not be affected. The operation of relay 4—M completes the circuit of relay T, the action of which closes the tip and sleeve conductors and completes the circuit between the calling and called subscribers' lines. The circuit of the cut-off relay of the called-for line, which corresponds to relay N of Fig. 2, is operated by the following path: ground, contacts of relay 1—C, (which was restored by the action of relay 4—M) 107, contacts of relay 3—M, 106, test wiper 105 to the winding of cut-off relay N to battery B. The operation of this latter relay disconnects battery from the relay A and ground from the coil I, thus clearing the tip and sleeve conductors of the called-for line. The operation of relay 4—M completes

the circuit of the ringing relay Z. This latter relay is operated intermittently by the commutator 200 and when operated connects generator current to the called-for line.

When the called subscriber removes his receiver in response to the call, tip relay Q is operated. The operation of this relay opens the locking circuit of relay 2—M and this latter relay in restoring opens the circuit of ringing relay Z.

At the termination of the conversation, the called subscriber replacing his receiver causes relay Q to restore. The restoration of this relay completes the circuit of the release magnet P by the following path: ground, cam springs 101, 72, back contacts of relay Q, 71, back contacts of relays 2—M and 1—C, 74, winding of magnet P to battery B. The operation of this magnet causes the switch X to restore to its normal position. The switch in reaching its normal position opens cam springs 101, thereby causing relay 4—M to restore.

The calling subscriber replacing his receiver causes relay 1—A to restore. This relay in restoring connects battery between the winding of relay Y and the coil 100 by the following path: battery B, contacts of relay 1—C, 62, contacts of relay Y to the winding of coil 100 and the winding of relay Y. The effect of battery being applied in this manner shunts the coil 100, thereby allowing the release magnet H of the first selector switch J to be operated. The operation of this magnet H causes the restoration of the switch J and also removes ground from the locking contact of relay M causing it to restore. The restoration of switch J removes ground from the winding of relay Y, thereby allowing it to restore, and it in restoring removes the shunt from coil 100.

In case the calling subscriber replaces his receiver first, the first selector switch J is released in the manner previously described and the called subscriber retains control of the connector switch X. If, however, the called subscriber does not respond then the connector switch X, as well as the first connector switch J, is under control of the calling subscriber. In the latter event the release of the switch X is effected by the circuit of the release magnet P being operated by the following path: ground, cam springs 101, 72, contacts of relay Q, 71, contacts of relay 1—A, 73, contacts of relay 1—C, 74, winding of magnet P to battery B.

Referring to Fig. 4, it will be noted that the last set of designating contacts are shown connected to ground. This ground connection is provided in case the calling subscriber should start the operation of the apparatus and then replace his receiver before connection is established. Relay L (Fig. 2) is shown provided with an armature which

controls the starting circuit for stepping magnet E of the switch J. The connection is shown in dotted lines in multiple with the connections on relay K. The same provision

5 is made in connection with the connector switch (Fig. 3) as relay S is provided with a set of contacts connected in multiple to similar contacts on relay R.

In case the calling subscriber should remove his receiver and then fail to operate his sending device relay C (Fig. 2) would be operated as well as relay L. Relay C is operated at the energization of relay A and relay L operated at the deenergization of 15 relay A. In such an event relay L being operated would complete the circuit of the rotary magnet E and cause the switch J to rotate until the wiper 33 engages the permanently grounded designating contact. As 20 soon as this contact is engaged relay M operates in the manner previously described and the switch J will then automatically select an idle switch. As soon as such a switch is selected the release magnet H would be operated in series with the winding of relay Y as relay 1-A would be deenergized as 25 the receiver of the calling subscriber is replaced.

In case the calling subscriber should replace his receiver after a connector switch 30 is selected relay 1-A would be deenergized and thereby operate relay S. Relay S would complete the starting circuit for stepping magnets of the switch X and this switch 35 would rotate until the last row of designating contacts, which is grounded, is reached. After this operation the switch X would then step vertically until the last designating contact in the row is engaged, whereupon relay 3-M would become energized and operate relay 4-M. The operation of 40 this latter relay would restore relay 1-C, thereby allowing relay Y and the release magnet H to be placed in series and the operation of the magnet would cause the switch J to restore. The restoration of relay 1-C also allows the circuit of the release magnet P of the switch X to be completed.

From the foregoing it will be noted that 50 after the tip relay of a selector or a connector switch is operated and should the calling subscriber replace his receiver the initial starting circuits for the switches is completed and they will step just as though 55 the subscriber had actually operated his sending device.

The designating devices, whether consisting of step-by-step relays or step-by-step switches should respond to impulses delivered at a faster rate of speed than the stepping of the main switches. The speed of the main switches can be controlled by proper 60 adjustments or other means well known in the art. Instead of depending entirely upon

speed adjustments the wipers of the main 65 switches can be set back so that several steps are required before the wipers engage the first contact.

Having thus described my invention what I desire to secure by Letters Patent is: 70

1. In a telephone exchange system, the combination with an automatic switch and a control circuit therefor, of means individually associated with said switch for designating any one of a number of contacts 75 thereon by changing the electrical condition thereof, a sender associated with said control circuit for variably actuating said designating means, and additional means for said switch for selecting the designated contact. 80

2. In a telephone exchange system, the combination with an automatic switch having associated contacts, designating means individual to said switch for automatically rendering selectable at will a particular contact therein by changing the electrical condition thereof, a sender adapted to operate the same, and additional means associated with said switch for selecting the particular contact, substantially as set forth. 85

3. In a telephone exchange system, the combination with an automatic switch having associated contacts, of a control circuit for said switch, of designating means individual to said switch, a sender in said control circuit for operating at will said designating means to automatically render a particular contact in said switch selectable by changing the electrical condition thereof, and additional means associated with said 95 switch for selecting the particular contact, substantially as set forth. 100

4. In a telephone exchange system, the combination with an automatic switch having associated contacts, of means associated 105 with said switch for selecting said contacts, additional step-by-step means individual to said switch for rendering a particular one of said contacts selectable by said selecting means by changing the electrical condition 110 of said particular contact, and a sender adapted to operate the same, substantially as set forth.

5. In a telephone exchange system, the combination with an automatic switch having associated contacts, designating means individual to said switch for rendering any one of said contacts selectable by changing the electrical condition thereof, a control circuit for said switch, a sender therein, means associated with said control circuit and operated by said sender for automatically operating said designating means to render any one of said contacts selectable by said switch, substantially as set forth. 115

6. In a telephone exchange system, the combination with an automatic switch having a bank of contacts, of an auxiliary step-

by-step device individual to said switch for rendering a particular contact in said bank selectable by changing the electrical condition thereof, a sender adapted to operate the 5 same, and additional means associated with said switch for thereafter selecting the particular contact, substantially as set forth.

7. In a telephone exchange system, the combination with an automatic switch having 10 a bank of contacts, an auxiliary step-by-step device individual to said switch for designating any one of said contacts by changing the electrical condition thereof, a sender for operating said auxiliary device, 15 additional means associated with said switch for selecting said designated contact after the operation of the auxiliary device, substantially as set forth.

8. In a telephone exchange system, the combination with an automatic switch having 20 a bank of contacts, of an auxiliary step-by-step device individual to said switch, of a control circuit for said switch, a sender therein adapted to operate said auxiliary 25 device to designate a particular contact in said bank by changing the electrical condition thereof and additional means associated with said switch for selecting the designated contact, substantially as set forth.

9. In a telephone exchange system, the combination with an automatic switch having 30 a bank of contacts, of a control circuit extending to said switch, a sender therein, of an auxiliary step-by-step device individual to said switch and controlled by said 35 sender for designating a particular contact in said bank by changing the electrical condition thereof, and additional means associated with said switch for selecting the 40 designated contact, substantially as set forth.

10. In a telephone exchange system, the combination with an automatic switch having 45 a bank of contacts selectable thereby, of a metallic control circuit for said switch, a sender therein, an auxiliary step-by-step device individual to said switch and controlled by said sender to designate the particular contact in the bank to be selected by 50 said switch by changing the electrical condition of said particular contact, substantially as set forth.

11. In a telephone exchange system, the combination with an automatic switch having 55 an associated bank of contacts, of a two-conductor metallic circuit for said switch, means individual to said switch and responsive to makes and breaks in said circuit for rendering a particular contact in said 60 bank selectable by changing the electrical condition thereof, additional means associated with said switch for selecting said contact, substantially as set forth.

12. In a telephone exchange system, the combination with a plurality of calling and 65

called subscribers' lines, means comprising automatic switches for connecting said lines, a set of step-by-step relays individual to each of said automatic switches, impulse sending means for controlling the step-by-step relays, and additional means whereby the automatic switches assume positions controlled by their respective sets of relays, substantially as set forth. 70

13. In a telephone exchange system, automatic switches having associated sets of contacts, sets of step-by-step controlling relays for said switches adapted to determine in advance the particular contacts to be selected by said switches, a sender for operating said relays, and means associated with said switches for selecting the designated contact, substantially as set forth. 75

14. In a telephone exchange system, subscribers' lines, connective links therefor provided with automatic switches, impulse actuated means associated with said switches, contact banks for said switches, means controlled by said impulse actuated means for variably designating contacts in said banks 80 by changing the electrical condition of said contacts, and means for causing said switches to move to a position corresponding to the designated contact. 85

15. In a telephone exchange system, subscribers' stations and a central station and metallic circuits interconnecting them, automatic switching apparatus at the central station for interconnecting lines, designating devices individual to said switching apparatus, means at each subscriber's station for varying the flow of current over the two sides of his line in series to produce groups of impulses varying in number according to a predetermined code, said designating devices being responsive to said impulses in the metallic circuit to designate by changing the electrical condition thereof the switch contacts to be selected by said switching apparatus whereby said switching apparatus 100 effects connections corresponding to the code changes produced by a calling subscriber, substantially as set forth. 105

16. In a telephone exchange system, a connector switch, a release magnet, a metallic circuit having answering and calling ends, a relay arranged to be energized by current over the answering end of said metallic circuit, a relay arranged to be energized by current over the calling end of said metallic circuit, means controlled by both of said relays when deenergized to operate said release magnet, and means controlled by only one of said relays when deenergized to operate said release magnet. 115

17. In a telephone exchange system, a calling line, a called line, a metallic circuit having answering and calling ends, means for connecting said calling line to said answering end, a connector switch for con- 120 125 130

necting said calling end to said called line, means for completing a talking connection between said lines, a relay arranged to be energized by current over the answering end 5 of said metallic circuit, a relay arranged to be energized by current over the calling end of said metallic circuit, a release magnet, a circuit for said magnet completed through the armatures and back contacts of 10 both relays in series before the completion of a talking connection between said lines, and a circuit for said magnet completed through the armature and back contact of only one of said relays after the completion 15 of a talking connection between said lines.

18. In a telephone exchange system, the combination with an automatic switch having associated test contacts, releasing means for said switch, a control circuit extending 20 to said automatic switch, means associated with said test contacts comprising a relay and a resistance coil having their windings in series, means exercised over said control circuit for short circuiting said resistance 25 coil through contacts of said relay to effect the release of the automatic switch, substantially as set forth.

19. In a telephone exchange system, the combination with an automatic switch having 30 associated test contacts, of releasing means for said switch, a control circuit extending to said switch, means predeterminedly associated with said contacts having an appreciable resistance, means exercised over said control circuit for diminishing said resistance to affect the releasing means of said automatic switch over said test contacts, substantially as set forth.

20. In a telephone exchange system, subscribers' stations and a central station, automatic switching mechanism at the central station for interconnecting said lines, designating devices individual to said switching mechanism, a two-conductor control circuit, 45 means associated with said control circuit for varying the flow of current over the two sides of said control circuit in series to produce groups of impulses varying in number according to a predetermined code, said 50 designating devices being responsive to said impulses in said circuit to designate by changing the electrical condition thereof the switch contacts to be selected by said switching mechanism whereby said switching 55 mechanism effects connections corresponding to the code which is produced by said means in said control circuit, substantially as set forth.

21. In a telephone exchange system, the combination with automatic switching mechanism having associated contacts, designating devices individual to said switching mechanism, a two-conductor control circuit, sending means associated with said control circuit for varying the flow of current 60

over the two sides of said control circuit in series to produce groups of impulses varying in number according to a predetermined code, said designating devices being responsive to the impulses in said control circuit 70 to designate by changing the electrical condition thereof the contacts to be selected by said switching mechanism whereby said switching mechanism assumes positions corresponding to code changes produced by 75 said sending means, substantially as set forth.

22. In a telephone exchange system, the combination with automatic switching mechanism, designating devices individual to said 80 switching mechanism, a two-conductor control circuit, means associated with said control circuit for varying the flow of current over the two sides of said control circuit in series according to a predetermined code, 85 said designating devices being responsive to said variation of current for rendering selectable certain contacts of said switching mechanism by changing the electrical condition of said contacts, and means for causing the automatic switching mechanism to be set upon said contacts, substantially as set forth.

23. In a telephone exchange system, the combination with an automatic switch, a 95 device individual to said switch for designating the position to be assumed by said switch, electromagnetic motive means for said switch, means for operating said designating means step-by-step in accordance 100 with a predetermined code, and additional electromagnetic means for disabling said motive means when the automatic switch assumes a position designated by said device, substantially as set forth. 105

24. In a telephone exchange system, the combination with an automatic switch having associated contacts, a designating device individual to said switch for changing the electrical condition of any of said contacts 110 to select the position to be assumed by said switch, electromagnetic motive means for said switch, and a sender for variably operating said designating device step by step in advance of said motive means. 115

25. In a telephone exchange system, the combination with an automatic switch, a designating device individual to said switch, electromagnetic motive means for said switch, means for operating said designating device step-by-step in accordance with a predetermined code, electromagnetic means associated with said switch for disabling the motive means when it assumes a position corresponding to that of the designating device in accordance with said code, substantially as set forth. 120

26. In a telephone exchange system, the combination with an automatic switch having associated contacts, a designating device 125

130

individual to said switch for changing the electrical condition of any of said contacts to select the position to be assumed by said switch, electromagnetic motive means for 5 said switch, and a sender for variably operating said designating device step by step at a speed greater than that of said motive means.

- 10 27. In a telephone exchange system, the combination with an automatic switch having associated contacts, an auxiliary device individual to said switch responsive to current impulses transmitted according to a predetermined code, self-acting electromagnetic 15 actuating means for said switch, electromagnetic means controlled by said device for disabling said actuating means when said switch engages a contact corresponding to said code, substantially as set forth.
- 20 28. In a telephone exchange system, the combination with an automatic switch, a designating device individual to said switch, said device responsive to current interruptions transmitted in accordance with a predetermined code, self-acting electromagnetic 25 actuating means associated with said switch, electromagnetic means controlled by said designating device for disabling said actuating means when the switch assumes a position corresponding to said code, substantially as set forth.
- 30 29. In a telephone exchange system, the

combination with a device for producing a predetermined number of signals, of an automatic switch provided with a plurality 35 of contacts, an auxiliary designating device individual to said switch and responsive to said device for rendering any one of said contacts selectable by said switch by changing the electrical condition of said 40 contacts, additional means associated with said switch for thereafter selecting contacts rendered selectable by said designating device, substantially as set forth.

30. In a telephone exchange system, the 45 combination with a two-motion automatic switch having associated contacts, an auxiliary device individual to said switch responsive to current impulses transmitted according to a predetermined code, self-act- 50 ing actuating means for operating said switch in both directions, and means controlled by said auxiliary device for changing the electrical condition of any of said contacts to determine the positions to be assumed by said switch in accordance with said code.

In testimony whereof I affix my signature in presence of two witnesses.

JOSEPH L. WRIGHT.

Witnesses:

ANNA McCUNE,
ADA DEHN.
